Application September 5, 1940, Serial No. 355,502

30 Claims. (Cl. 149—17)

This invention relates to machines for operating upon hides, skins, leather, and other sheet material. While the invention is illustrated as embodied in a machine for operating a glazing tool back and forth over a tanned hide or skin, it is to be understood that the invention and various important features thereof may have other applications and uses.

In commercial glazing machines, as heretofore constructed, the glazing tool has been carried back and forth over a work piece by a lever moving as a pendulum while the work piece rests upon a flat surface. In such an arrangement the stroke of the lever has been constantly through the same length of arc irrespective of the dimensions of the work piece. Also, in certain types of leather brushing, rolling, stoning, and whitening machines, the tool is moved back and forth a fixed distance irrespective of the linear dimensions of the work pieces. Hence, much of the operative stroke of these different tools is wasted where the work piece is so dimensioned and positioned that the travel of the tool thereon is short, while in other cases the entire stroke of the tool produces its effect on the work piece. From the very nature of the swinging movement of the tool in the pendulum type of machines, it moves at a faster rate in certain parts of the arc than in other parts. This lack of uniformity in the rate of travel of the tool over the surface of the work piece is not conducive to uniform results. Furthermore, in glazing machines of prior constructions no very satisfactory provision has been made to secure in glazing operations a pressure suited to variations in the thickness dimensions of the work piece.

It is an object of this invention so to control a work treating tool that the length of its operative stroke will vary according to the dimensions of the work piece along the various paths of the tool over the surface of the work piece. It is a further object of the invention to provide a sensitive adjustment of the pressure of a work treating tool with respect to various thicknesses of the work piece undergoing treatment. Still another object of the invention is to provide an improved machine in which the tool will travel at a uniform rate during the operative stroke thereof, thereby contributing to uniformity in the effects obtained. Whereas, in most machines now in use in the tanneries, the work piece has to be manipulated by the operator to secure treatment of successive portions therein, it is an object of this invention to provide special

means for shifting the work piece between the strokes of an oscillating or reciprocating tool.

Accordingly, it is an important feature of the invention that the stroke of a work treating tool is controlled with reference to a linear dimension of the work piece in the direction of travel of the tool so that the tool may promptly return for a succeeding work treating stroke. An advantage of this construction resides in the fact that throughout the operative strokes of the tool useful work is performed, whereas heretofore the tool has been carried through a certain definite path although it might be treating a work piece only through a part of such path. For controlling the tool, a detector means is provided which moves in advance of the tool and controls the tool operating means to determine the length of the operative stroke of the tool and to reverse the tool promptly when it reaches the edge of the work piece.

Another feature of importance in this invention relates to the provision of a sensitive means for varying the pressure of the work treating operation in accordance with variations in the thickness dimension of the work piece in the path of a tool. Conveniently, a feeler member contacting the work piece in advance of the tool exercises control of a mechanism for causing relative approaching and separating movements between the tool and a work supporting member. In the illustrated construction, the work support is movable to press the work piece against the tool and is arranged to be retracted away from the tool when thinner and more compressible portions of the work piece are presented for treatment, while thicker and denser portions of the work piece receive heavier pressure during the work treating operation.

Another important feature of the invention resides in the provision of means for shifting a work piece between operations of a work treating tool, a preferred construction being that in which the work shifting means also places a portion of the work piece under tension wherein it is held during a given work treating operation by the tool.

For securing operations of the tool, of the work support, and of the work shifting means in timed relation to each other there is provided a hydraulic mechanism under the control of special valve mechanisms. In such an arrangement, a simple and effective hydraulic means is provided for securing movement of the tool at a uniform rate in its operative strokes, thereby contributing to uniformity in work treating

operations upon various parts of the work piece.

These and other important features of the invention and novel combinations of parts will now be described in detail in the specification and then pointed out more particularly in the appended claims.

In the drawings,

Fig. 1 is a view in side elevation and partly in section of a glazing machine illustrating one embodiment of the invention;

Fig. 2 is a front view of the machine shown in Fig. 1;

Fig. 3 is a plan view looking down from above on the machine shown in Figs. 1 and 2; and

Fig. 4 is a detail view of a valve mechanism utilized in the control of the hydraulic pistons of the machine.

In the illustrated machine, which is specially designed to perform glazing operations upon tanned hides and skins, there is provided a table 6 for supporting a work piece while it is being treated by a glazing tool 8 (Fig. 1). The tool 8 is a glass roll of the type well known in commercial glazing machines. As shown, it is firmly clamped against rotation, by a clamping member 10, fixed to the forward end of a head or carrier 11 which is slidable in the frame 12 of the machine on dove-tailed guideways best shown at 14 in Fig. 2.

For controlling the length of the operative stroke of the tool 8, the illustrated machine is provided with novel detector means comprising, in the construction shown, a feeler member 16 at the forward end of a lever 18 pivoted at 20 on the head or carrier 11. As shown, the feeler 16 is a forked member, the forward ends of which are substantially in alignment with a plane passing vertically through the axis of the tool 8. At its rear end the lever 18 is provided with a roll 22 which rides along the upper surface of a controller member 24 yielding supported by a spring 25 and carried by the upper end of a rod 26 slidable vertically in suitable bearings 27 in the frame of the machine. When the feeler or detector member 16 drops off an edge of the work piece during movement of the tool 8 and of the head 11 to the right in Fig. 1, means (hereinafter described) is operated to terminate the operative stroke of the tool as soon as it reaches an edge of the work piece and to return the tool idly for a succeeding stroke across the surface of the work piece.

For operating the tool 8 at a uniform rate in its operative stroke, I have provided hydraulic means comprising a rack member 30 arranged to be reciprocated by piston heads 31, 33 at opposite ends of the member 30. While, for cheapness of construction, the heads or pistons 31, 33 are shown as made separate from the member 30, they may be made integral therewith. In any case, the member 30 with the heads 31, 33 may be regarded as a piston member or device having a rack portion 32 to operate the tool 8. As shown, the rack 32 is arranged to be constantly in mesh with a segmental rack 34 secured to a shaft 36 rotatable in bearings in a stationary oil-tight casing member 38 secured to the frame of the machine. Secured to the end of the shaft 36 outside of the casing is a lever 40 which at its upper end is pivotally connected at 42 to a link 44 which is pivotally connected at its forward end to the head or carrier 10 by the pivot pin 20. When the rack member 30 is reciprocated back and forth in its casing 50, the lever

40 is rocked to cause corresponding reciprocatory movement of the head or carrier 11 and hence of the glazing tool 8. During the operative stroke of the tool 8 to the right in Fig. 1 it operates on a work piece on the table 6 while, during the return stroke of the tool to the left, the table 6 is depressed, by means hereinafter described, to prevent engagement of the tool with the work during its return stroke, the table 6 being moved upwardly into its elevated or operative position just prior to the beginning of the next operative stroke of the tool. For reciprocating the rack member 30, hydraulic medium under pressure is admitted alternately to piston cylinder heads 52, 54 through pipes 56, 58, respectively, opening through ports in the cylinders 52 and 54, respectively. The other ends of the pipes 56 and 58 open into a chamber of a valve mechanism 60 which receives pressure medium, such as oil under pressure, from a pump 62 through a pipe 64 which opens into the valve chamber 60 through a port located at a middle part of the length of the valve chamber, the pump being driven by any well-known power means such as a motor 61.

As shown most clearly in Fig. 4 of the drawings, the valve chamber has slidably mounted therein a hollow valve member 66 having a middle portion of reduced diameter so that liquid medium entering through the pipe 64 may pass in either direction to the ends of the chamber and out alternately through either of the pipes 56 and 58, depending upon the position of the movable valve member 66. When the valve member 66 is moved to the left in Figs. 1 and 4, the pressure medium flows through pipe 56 to the cylinder 52 and causes movement of the rack member 30 to the right during which the liquid flows from the head 54 through the pipe 58 to the valve casing of valve 60 and into the hollow movable valve member 66 and thence out through a pipe 68 to a sump 70. Upon movement of valve member 66 to the right, the liquid flows from pipe 64 to pipe 58 and moves the member 30 in the reverse direction i. e., to the left, during which the pressure liquid escapes from cylinder 52 through the pipe 56 to the sump pipe 68. It is to be noted that the valve member 66 when in its central position (Fig. 4) covers the openings of the pipes 56 and 58 and that the least movement of the member 66 to the right permits liquid to pass from pipe 64 to and through pipe 58, while an equally small movement of the valve member 66 to the left directs liquid under pressure from pipe 64 to the pipe 56. The result is a sensitivity of valve action that produces instantaneous action in the hydraulically operated members.

When a piece of work on the table 6 is carried up into firm contact with the glazing tool 8 through the elevation of said table, the feeler or detector member 16 is lifted by the work piece with the result that the rear end of the lever 18 is depressed, thereby effecting downward movement of the controller member 24 and of the rod 26 secured to its lower surface. Downward movement of the rod 26 has the effect of rocking a bell crank lever 74 (Fig. 1) in a clockwise direction. Since the upper end of the lever 74 is connected to a valve rod or stem 76 by means of a collar 78 slideable on the rod 76 against the tension of a spring 80, it follows that downward movement of the rod 26 is accompanied by movement of the rod 76 and of the connected valve member 66 to the right in Fig. 1, with the result

that pressure medium under pressure entering the valve chamber 60 through the pipe 64 may pass through the valve chamber and out through the pipe 58 to the cylinder 54 where it acts upon the piston 33 therein to move the rack member 30 to the left in Fig. 1, thereby effecting the operative stroke of the glazing tool 8. With respect to the valve member 66 in valve device 60, it is important to note that the thinnest skin or skin portion will cause the feeler 16 to move the valve member 66 fully to the right in Fig. 1, and that thicker work parts will simply compress the spring 80 further, without oscillating the valve member 66. To limit movement of the valve to the right, and to prevent overthrow of member 66 there is provided a stop member 81 adjustable toward the adjacent end of the piston rod 16. On the other hand, when the feeler 16 drops off an edge of the work piece, the controller member 24 rises under the action of the spring 25 with the result that the bell crank 74, piston rod or stem 16 and valve member 66 move to the left (Fig. 1) whereby the hydraulic medium under pressure passes through the pipe 56 to the cylinder head 52 to effect instantly movement of the rack member or piston 30 to the right thereby causing the return or idle stroke of the glazing tool 8. It should be noted in this connection that spring 80 (Fig. 1) holds the slideable collar 78 against a stop collar 82 pinned to the valve stem 16. During this return stroke of the tool, the work support 6 is lowered with the result that the tool does not operate on the work piece. Furthermore, the tool 8 remains at the left end of its stroke while the machine is in rest position, as shown in Fig. 1.

Hydraulic means is also provided for operating the work support in timed relation to the glazing tool. In the illustrated construction, such hydraulic means comprises a valve mechanism 90 similar in all respects to the valve mechanism 60. Fluid under pressure travels from the constantly operating pump 62 to the valve mechanism 90 through the pipe 64 and branch pipe 92, the latter entering the middle portion of the valve chamber and being directed therefrom through a pipe 94 to a cylinder head 96 whereby a piston 97 is instantly forced to the left (Fig. 1) to operate rack member 98. As in the case of the tool-operating piston 30, the rack member 98 is provided with rack teeth which are constantly in mesh with the segmental gear 100 secured to a shaft 102 journaled in an oil-tight stationary casing 104. To an end of the shaft 102 outside of the casing is secured the lever arm 108 which is forked to embrace a collar 110 slideable on a post 112 to the upper end of which is secured the work support 6. Interposed between the collar 110 and an enlarged part 114 of the post 112 is a heavy spring 116. When the collar 110, which is engaged by pins carried by the lever arm 108, is lifted by said lever arm the spring 116 is compressed and forced upwardly to effect upward movement of the post 112 and hence of the table 6. In other words, the spring 116 serves as the actual pressure means by which the work piece is supported against the thrust of the tool 8. This same lever arm 108 is provided with pins 120 which engage in a slot 122 of a sleeve member 124 slideable on a second post 126, upward movement of the sleeve 124 having the effect of compressing a light spring 127 to effect upward movement of a work clamping and moving means which will be hereinafter described in detail.

As pointed out above, movement of the rack or

piston member 98 to the left in Fig. 1 results in upward movement of the work support 6 into cooperative relation with respect to the glazing tool 8. At the end of the upward movement of the work support 6, the feeler member 16 is lifted just before the work piece contacts the tool 8. Such lifting of the feeler member 16 results in downward movement of the controller 24 whereby an operative stroke of the tool 8 is initiated. As heretofore pointed out, the feeler 16 travels with the tool 8 in its operative stroke and reaches the edge of the work substantially at the same time as the tool, so that it drops off said edge of the work and initiates the return stroke of the tool as soon as the latter drops off the edge of the work, this practically instantaneous response of the hydraulic means to the position of the feeler 16 being due to the extreme sensitivity of the valve mechanism 60. During this return stroke of the tool the table 6 is depressed, this result being attained through control of the valve mechanism 90 by the feeler 16. As soon as said feeler drops off the edge of the work, the controller member 24 is lifted by the spring 25 with the result that a link 130 pivoted at 131 to the lower end of the rod 26 is moved upwardly about a pivot 132 stationary at that time. This upward movement of the link 130 has the effect of lifting a valve rod or stem 136 (connected to the link 130 by a pin 133 secured to the link 130 and operating in a grooved spool 135) slideable on the valve stem 136 thereby shifting the valve member inside of the valve chamber 90 in a direction to cause the pressure medium to move through the valve mechanism to a pipe 140 opening at its other end into a piston cylinder head 142 whereby the rack member or piston 98 is instantly operated in the reverse direction, that is, to the right in Fig. 1, whereby the work support 6 is lowered and with it the work clamping devices. It is pointed out that the spool 135 is yieldingly held against a collar 137 pinned to the end of the valve stem 136 by a spring 139. At its other end, the spring 137 presses against a block 159 fastened to the stem 136. During the interval that the work support 6 is lowered, the tool 8 returns to its extreme left position in Fig. 1 in its idle stroke.

While the valve mechanism 90 controls the rack member or piston 98 for effecting movement of the work support 6 between work receiving and work presenting positions with respect to the tool 8, the said valve mechanism 90 and the member 98 are also controlled in such manner as to vary the pressure with which a given work piece is pressed against the tool 8 during the operative stroke of the latter. It will be noted that the feeler member 16 is located closely adjacent to the tool 8. As it travels over the surface of the work piece with the tool 8 it responds to variations in the thickness dimension of the work piece in its path over the latter. The result is that the controller member 24 moves slightly in up-and-down directions corresponding to the movements of the feeler 16. Hence the hollow valve member in the valve mechanism 90 is shifted accordingly and thereby varies the flow of liquid under pressure through the pipe 94 to the piston cylinder 96 and hence varies the pressure by which the work support 6 presents the work piece against the tool 8.

When, for instance, a thin spot is contacted by the feeler 16, the controller member 24 is lifted by the spring 25, with the result that link 130 is lifted about pivot 132, whereby valve stem 136 is moved upwardly together with the valve mem-

ber in valve 90. Hence liquid flows through pipe 140 to the cylinder head 142, thereby moving rack member 98 to the right a slight amount, causing downward movement of lever arm 108 and hence of the work support 6. But a link 141 pivoted to lever arm 108 is also pivoted at its other end to a lever 143 pivoted at 145 to the frame of the machine. The free end of lever 143 is pivoted to a link 147 pivoted on pivot pin 132 of link 130. Hence any downward movement of lever arm 108 and of the work support 6 will cause lowering of the valve stem 136 and hence of the movable valve member in valve 90 which is thus returned to neutral position. In other words, the rack member 98 is hydraulically lock in the new position which puts a little less pressure on the spring 116 which supports and delivers the necessary pressure on the leather. By varying the tension of the spring 116 hydraulically, pressure on the work piece is varied in accordance with the thickness dimensions thereof. When feeler 16 dropped lower because of a thin spot, rod 26 moved upwardly and link 130 turned about 132 as a pivot to lift valve member in valve 90, thereby permitting flow of pressure medium through pipe 140 to lower the lever arm 108 and work support 6. But lowering of arm 108 lowers lever 143 about pivot 145, thereby lowering link 130 about pivot 131 which had been lifted when feeler 16 engaged the low spot. Hence link 130 rocks about pin 131 and brings valve member in valve 90 to neutral position with the piston 98 hydraulically locked against movement, thus maintaining upward pressure on spring 116 to support the table 6. This mechanism affords a very sensitive adjustment of the glazing tool to variations in the thickness dimension of the work piece in the path of the feeler and tool. In the illustrated construction, this pressure is slightly less for thinner portions of the work piece than it is for thicker portions thereof.

As a safety feature, for instance, if the operator does not center a skin properly, or if a skin is too large for the machine, the feeler 16 may not drop downwardly at the end of its stroke to the right. However, it is necessary to reverse the stroke and to lower the table, otherwise the machine would be locked against further operation. Hence a link 151 is pivoted to the lever 49 and to a bell-crank 153 through a slotted part 155 of link 151, the latter permitting a normal stroke of the tool 8 and feeler 16, after which the shoulder at the left end of the slot 155 will operate the bell crank 153. Operation of bell crank 153 lifts a link 153a pivoted at its lower end to a block 159 fixedly secured to the stem 136 of the movable valve in the valve device 90. Lifting of the valve member in valve 90 sends liquid through pipe 140 and effects lowering of the work support, thus conditioning the machine for a succeeding operation.

As heretofore indicated, the illustrated machine preferably embodies work clamping and moving means, the purpose being to shift the work piece after each operative stroke of the glazing tool 8. This makes the machine automatic in its operations on a given piece of work, whereas heretofore the operator had to shift the work piece between successive strokes of the operating tool. In the illustrated construction, the work clamping means comprises work clamping members 150, 152 (Fig. 2) carried by hubs 154 and 156, respectively, the said hubs being rotatably mounted upon the upper end of the post

126 and held against movement lengthwise of the post 126 by collars 157. A spring 158 is connected to pins on both of the members 150, 152 to hold these members yieldingly toward each other. For co-operation with the work clamping members 150, 152 which are movable upwardly with the post 126, there is provided a pair of work clamping members 160, 162 carried by hubs 164 and 166, respectively, the said hubs being rotatable on a vertical stub shaft 168 but being restrained against up-and-down movement. The work clamping members 160, 162 have connected therewith a spring 170 which holds the members 160, 162 yieldingly toward each other.

It will be readily understood that the work clamping members 150, 152 move upwardly and co-operate with the work clamping member 160, 162 well before the work support 6 presents the work piece to the tool 8. In fact, means is provided for rotating the work clamping members after they engage the work piece so as to shift the latter over the surface of the work support 6 to present another portion thereof for the next stroke of the tool. At the end of the sidewise swinging movement of the work clamping members 150, 152 and 160, 162, the latter are operated to separate or recede laterally from each other so as to place that portion of the work piece between them under tension while the tool is operating. The means for accomplishing these operations will now be described.

As shown most clearly in Fig. 2, the hub 156 of the work clamping member 152 has a projecting ear 171 thereon to which is connected a link 180 having an opening in its outer end for the reception of an upstanding pin 182 secured to the end of a link member 184 pivoted at the forward end of a slide member 185 (Figs. 1 and 2). By having the pin 182 of substantial length, the connection between the link 180 and the link member 184 is maintained at all times, that is, during upward and downward movement of the work clamping members on the post 126. Movement of the link member 184 to the rear in Fig. 1 will result in swinging the work clamping members in a clockwise direction (Fig. 3) to shift the work piece over the upper surface of the work support 6. This operation of the work clamping members 150, 152 will be better understood upon reading the following description of the clamping members 160, 162 which are also shown more clearly in the plan view of Fig. 3. In order that the upper work clamping members 160 and 162 may be positively rotated at the same time as the lower clamping members, the hub 166 of the work clamping member 162 is provided with an ear 186 (Figs. 2 and 3) to which is pivoted a link 187 in turn pivoted to the forward end of a link member 190 at the forward end of a slide member 191. Similarly, hub 164 (Fig. 2) has an ear 193 (Figs. 2 and 3) to which is pivoted a link 195 pivoted at its other end to lever 187. These slide members 185 and 191 are moved rearwardly in Figs. 2 and 3 to rotate the work clamping members after they have engaged the work piece. At the end of this swinging or rotating movement of the work clamping members, terminated by the upper member 162 coming into contact with a side edge of the table 6 (Fig. 3), they are caused to move away from each other in sets upon opposite sides of the table 6 to tension a portion of the work piece between them so that the work piece is properly conditioned for treatment by the glazing tool 8.

The described separating movement of the sets of work clamping members is accomplished through the operation of a lever mechanism most clearly shown in Fig. 3. Upon reference to Fig. 3 it will be observed that the ear 186 on the hub 166 is movable about the shaft 168 and has pivoted to its end a lever member 187 to which is pivoted the short link 195 also pivoted to an ear 193 rigid with the hub 164 of the work clamping member 160. It will be clear that clockwise rotation of the lever 187 in Fig. 3 will result in straightening a toggle of which the link member 195 is the other member, the straightening of the toggle being accompanied by separating movement of the work clamping members 160, 162 to tension a portion of the work piece. It is to be understood that the lower work clamping members 150, 152 are operated in the same way simultaneously with the upper members 160, 162.

For operating the work clamping devices after they have engaged the work piece, there is preferably provided a hydraulic mechanism similar to that for operating the tool 8 and to that for operating the work support 6. This hydraulic mechanism comprises a valve mechanism 220 (Fig. 1) which is similar in all respects to the valve mechanisms 60 and 90. In this case, fluid under pressure comes from the pump 62 by a pipe 222 and a branch pipe 224 opening into the middle part of the valve casing of valve mechanism 220. The movable valve member inside the casing is controlled by a valve stem 226 having at its outer end a roller 228 in contact with a flat surface 230 on the sleeve 124. When the sleeve 124 is moved upwardly by the lever arm 108, the roller 228 rides along the flat surface 230 and also along a flat surface of a latch member 232. When the roller 228 drops off the lower end of the surface of the latch member 232, the valve stem 226 is projected to the left (Fig. 1) by a spring 234. This movement of the valve stem and movable valve member inside 220 results in passage of the pressure medium under pressure through a pipe 240 to a piston cylinder 242 (Fig. 3) which contains a piston to operate a rack 243 in casing 244 similar in all respects to the rack 30 and to the rack 98 of Fig. 1. In fact, the showing of the piston 30 and all its operating parts in Fig. 1 is also a disclosure of the piston in cylinder 242 and of the rack 243 in casing 244. Movement of this piston and rack in the casing 244 operates a lever 250 (Fig. 1) which is connected by a link 252 to the pair of slide members 185, 191 which in turn are connected at their front ends through links 184 and 190 to the lower and upper work clamping members 152 and 162, respectively, to operate the latter in the two successive movements described above. These movements of the clamping members are accomplished before the work support presses the work piece against the tool 8.

There has been described in the preceding paragraph the manner of operating the valve stem 226 (Fig. 1) which carries the roller 228, it being stated that upward movement of the sleeve 124 on the post 126 results finally in the dropping of the roller 228 off of the lower end of a flat surface on the latch member 232. During the subsequent downward movement of the sleeve 124, the roller 228 runs up a slanting surface 270 on the sleeve 124 until it lifts the spring pressed latch member 232 and reappears on the flat surface in the position shown in Fig. 1. It will be understood, of course, that downward movement

of the post 126 and of the sleeve 124 is accompanied by downward movement of the lower work clamping members 150, 152. During this downward movement the valve stem 226 is moved to the right, thus effecting a reverse movement of the valve member in the valve mechanism 220 with the result that pressure medium under pressure flows out through a pipe 272 whereby such pressure medium under pressure is introduced into a piston cylinder head 274 (Fig. 3) to move the rack 243 in casing 244 in the direction to swing the work clamping members to their initial positions, in which they are ready to clamp a work piece upon a subsequent upward movement of the lower clamping members.

When the machine is at rest, the valve member in valve device 90 is down so that liquid may enter cylinder head 96 to start lifting of the work support 6. Also valve member 66 in valve device 60 is over to the left in Fig. 1, while the machine is at rest, to hold the tool 8 over to the left while table 6 is down and while the latter is rising. Contact of the work piece with the feeler 16 starts operation of the tool 8. Also the work clamping members are held in the position of Fig. 1 by the rack or piston member 243 under control of the valve 220 as conditioned by the position of the valve stem 226 and roller 228 (Fig. 1).

To start the machine in operation, the operator steps on a tread portion 290 of a treadle shown in Fig. 2 of the drawings with the result that a toggle 292 is broken thereby lowering a spring loaded relief valve member 294 in a valve chamber 296. Such movement of the valve 294 stops the flow of liquid through a pipe 300 to the sump 70 with the result that liquid from the pump 62 is forced to pass upwardly through the pipes 64 and 224 to the valve mechanisms 60, 90 and 220, respectively, whereby the racks 30, 98 and 243, respectively, are actuated in timed relation to each other. As soon as the table supporting post 112 moves upwardly following the closing of the valve in valve device 296, a lever 310 (Fig. 2) is rocked by a spring 312 to project a latch 314 into a notch 316 in a member 318 fixed to the treadle, the result being that the treadle is locked with the valve in valve casing 296 in position to maintain the machine in operation while it is treating a given piece of work and until the treadle is moved in the opposite direction by the foot of the operator, it being understood in this connection that the toggle 292 will remain in broken condition in the brief intervals during which the work support is in lowered position. When the work support is in the lower position the treadle may be moved to the position shown in Fig. 2 to straighten the toggle and stop the operation of the machine. The toggle moves beyond center to hold the inoperative position shown in Fig. 2.

In operating the illustrated machine to glaze a kid skin, for instance, the latter is placed on the work support 6 with the center point in the backbone line of the skin directly under the tool 8. As the work support and lower work clamping members rise toward the tool, the work clamping members engage the skin and shift it laterally in the manner described before the work support presses the skin against the tool. Not only is the skin shifted but it is tensioned by a separating movement of the work clamping members before it is pressed against the tool. As the feeler 16 moves upwardly through pressure 70 of the skin backed by the work support it initi-

ates an operative stroke of the tool which is terminated as soon as the tool drops off the edge of the skin. The tool is then returned in its idle stroke which takes place while the work support is depressed along with the lower work clamping members. These members then rise again to engage the skin in its new position and to shift and tension it prior to the next working stroke of the tool. These operations are repeated until all portions of the skin have been successively presented for treatment. It is to be understood, of course, that a supplemental work support may be provided which will be stationary in the plane of the support 6 when the latter is in its raised position, this supplemental work support being of a size to furnish support for those parts of a hide or skin which normally would extend beyond the support 6, this arrangement insuring that the hide or skin will not be displaced by gravity in the intervals between the work clamping and shifting operations.

Having thus described my invention, what I claim as new and desire to secure by Letters Patent of the United States is:

1. In a machine for operating on sheet material, a work support, a tool movable in opposite directions relatively to a work piece on said support, said tool having an operative stroke in one direction and an idle stroke in the opposite direction, means for reciprocating the tool in its idle and operative strokes, and means controlled directly by the work piece with reference to a linear dimension thereof to terminate the operative stroke of the tool according to the length of said dimension.

2. In a machine for operating on sheet material, a work support, a tool movable in opposite directions relatively to a work piece on said support, said tool having an operative stroke in one direction and an idle stroke in the opposite direction, means for reciprocating the tool in its idle and operative strokes, and detector means controlled directly by the work piece with reference to a linear dimension thereof to initiate return of the tool in its idle stroke when said tool drops off an edge of the work piece.

3. In a machine for operating on sheet material, a work support, a tool movable in opposite directions relatively to a work piece on said support, said tool having an operative stroke in one direction and an idle stroke in the opposite direction, means for reciprocating the tool in its idle and operative strokes, and work-controlled detector means movable with the tool to determine the length of the operative stroke of the tool whereby the latter is reversed when it passes off an edge portion of the work piece.

4. In a machine for operating upon sheet material, the combination with a work support and a tool, of power operated means for imparting to said tool repeated movements in one direction in operating upon a work piece on said support, and work-controlled means for terminating each operative movement of the tool as soon as the tool is moved out of engagement with the work piece.

5. In a machine for operating on sheet material, a work support, a tool for operating on a work piece, means for reciprocating the tool in its idle and operative strokes, and work-controlled detector means spaced from said tool in the direction of its operative stroke and movable therewith to detect the approach of said tool with respect to an edge portion of the work piece and to initiate return of the tool in its idle stroke as

soon as the latter drops off the edge of the work piece.

6. In a machine for operating on sheet material, a work support, a tool for operating on a work piece, means for reciprocating the tool in its idle and operative strokes, work-controlled detector means to control the operative stroke of the tool whereby the tool is reversed when the latter passes off an edge portion of the work

piece, and means for causing relative separating movement of the tool and work support the instant the tool drops off said edge portion of the work piece whereby the return stroke of the tool becomes an idle stroke.

15 7. In a machine for operating on sheet material, a work support, a tool for operating on a work piece, means for reciprocating the tool in its idle and operative strokes, work-controlled detector means to control the operative stroke of the tool whereby the latter is reversed when it passes off an edge portion of the work piece irrespective of the length of such operative stroke, and means for lowering the work support the instant the tool passes off said edge of the work piece whereby the return stroke of the tool becomes an idle stroke.

8. In a machine for operating on sheet material, a work support, a tool for operating on a work piece, means for reciprocating the tool in its idle and operative strokes, detector means directly controlled by the work piece and operative to control the operative stroke of the tool whereby the tool is reversed when it passes off an edge portion of the work piece, said reciprocating means including a piston for operating the tool in one direction, and hydraulic means for operating the piston to move the tool at a uniform rate of travel over the surface of the work piece.

9. In a machine for operating on sheet material, a work support, a tool movable in a plane above the work support for operating on a work piece on said support, means for moving the work support toward and from the operative plane of the tool, detector means directly responsive to the presence and absence of a work piece on the work support and operative to control the operative stroke of the tool, a piston device for operating the tool, and hydraulic means under the control of said detector means for operating the piston device to move the tool at a uniform rate of travel over the surface of the work piece.

10. In a machine for operating on sheet material, a work support, a tool movable in a plane above the work support for operating on a work piece on said support, means for causing relative approaching and separating movements between the work support and tool during movements of the tool in its operative and idle strokes, detector means directly controlled by the work piece and operative to control the operative stroke of the tool whereby the tool is reversed when the latter passes off an edge portion of the work piece, a piston device including a rack for operating the tool, and hydraulic means under the control of said detector means for reciprocating the piston device alternatively in opposite directions, the relative separating movement of the work support and tool being timed to produce the idle stroke of the tool with respect to the work piece.

70 11. In a machine for operating on sheet material, a tool, a work support for a work piece during treatment thereof, means for moving the tool back and forth in a plane above the work support, a feeler device movable with the tool and

arranged to drop off an edge portion of the work piece before the tool reaches such edge portion, means controlled by the feeler device to reverse the direction of movement of the tool as soon as the tool drops off the edge of the work piece, and means to cause a relative separating movement between the work support and tool during the return movement of the tool so that such return movement is an idle stroke of the tool preparatory to a succeeding operative stroke thereof.

12. In a machine for operating upon sheet material, a work support, a tool movable over the surface of a work piece on the work support, means for moving said tool back and forth over the surface of the work piece, power means for causing relative approaching and separating movements of the work support and tool, and detector means operating in advance of the tool in the direction of its operative stroke to control the said power means in accordance with the thickness of the work piece in the path of the tool, whereby the pressure of the tool on the work piece may be suited to various portions thereof.

13. In a machine for operating upon sheet material, a work support, a tool, power means to move the tool over the surface of a work piece on the work support, hydraulic means comprising a valve mechanism for causing relative approaching and separating movements between the work support and tool, and a feeler device movable in advance of the tool during its work treating movement and operative to respond to variations in the thickness of the work piece in the path of the feeler and tool, said feeler device having connections to control said valve mechanism whereby the pressure between the work support and the tool is adjusted to the varying thickness of the work piece during movement of the tool over the work piece.

14. In a machine for operating upon sheet material, a work support, a tool movable in a plane above the surface of a work support to operate on a work piece on the support, power means for causing relative approaching movement between the work support and tool, power means for moving the tool back and forth in its operative and idle strokes, a feeler device contacting the work piece and movable in advance of the tool in its operative stroke, and connections between the feeler member and both of said power means whereby the feeler device controls not only the length of the operative stroke of the tool but also the pressure between the work support and tool in accordance with variations in the thickness of the work piece in the path of the tool.

15. In a machine for operating upon sheet material, a work support, a tool for treating a work piece while the latter is backed by the support, hydraulic means comprising a piston device having operative connections with said tool, cylinders for slidably receiving the opposite ends of said device, a valve mechanism to control the passage of pressure medium alternately to said cylinders whereby the piston device and the tool are reciprocated, a feeler device contacting the work piece and movable in advance of the tool in the direction of its operative stroke, and connections between the feeler device and said valve mechanism to control the latter whereby the piston device and hence the tool are reversed in their direction of movement when the feeler drops off an edge of the work piece.

16. In a machine for operating upon sheet material, a work support, a tool to operate on a

work piece backed by said work support, power means for causing relative approaching and separating movements between the work support and tool, power means for moving the tool along a given path on the surface of the work piece on the work support to treat that portion of the work piece in the path of the tool, a pair of work clamping members at each side of the work support, one member of each pair being above and the other below the plane of the work piece on said support, thus providing an upper and a lower set of work clamping members, means for causing the work clamping members to engage a work piece placed between them, and power means operating in timed relation to the two first-mentioned power means to move the pairs of work clamping members away from each other on opposite sides of the work support to place that portion of the work piece lying between the pairs of members under tension prior to each of the operative strokes of the tool.

17. In a machine for operating upon sheet material, a work support, a tool movable from a middle portion of a work piece to a margin thereof, power means for reciprocating the tool in its operative and idle strokes, a pair of work clamping members on each side of the work support, one of each pair being above and the other below the work supporting surface thereof, thus providing an upper and a lower set of work clamping members, power means for moving one set of work clamping members toward the other whereby the work piece is clamped by said clamping members, means for rotating the clamping members to shift the work piece in one direction over the surface of the work support prior to the operation of the tool, and means for moving the pairs of clamping members on each side of the work support away from each other sufficiently to place the work piece under tension prior to the operation of said tool.

18. In a machine for operating upon stretchy sheet material, a work support, a tool movable from a middle portion of a work piece to a margin thereof, a pair of work clamping members on each side of the work support, one of each pair being above and the other below the work supporting surface thereof, thus providing an upper and a lower set of work clamping members, power means for moving one set of work clamping members toward the other whereby the work piece is clamped by said clamping member, power means for rotating the clamping members to shift the work piece in one direction over the surface of the work support prior to the operation of the tool, means operating in timed relation to the rotating means for moving the work support in a direction to press the work piece against the tool, means for causing a relative separating movement of the pairs of clamping members on each side of the table to place the work piece under tension just prior to the pressing of the work piece against the tool, and means for operating the tool to treat the work piece while the latter is held under tension by the work clamping members.

19. In a machine for operating upon stretchy sheet material, a work support, a tool movable from a middle portion of a work piece to a margin thereon, a pair of work clamping members on each side of the work support, one of each pair being above and the other below the work supporting surface thereof, thus providing an upper and a lower set of work clamping members, power means for moving one set of work clamping

members toward the other whereby the work piece is clamped by said clamping members, means for rotating the clamping members to shift the work piece in one direction over the surface of the work support prior to the operation of the tool, power means for moving the work support in a direction to press the work piece against the tool, means for causing a separating movement of the pairs of clamping members on each side of the work support to place the work piece under tension just prior to the pressing of the work piece against the tool, means for operating the tool to treat the work piece while the latter is held by the work clamping members, means for lowering the work support and at the same time returning the work clamping members to their initial positions whereby the work piece is released by both the work support and the work clamping members, the subsequent upward movement of the work support and of the lower set of work clamping members being accompanied by reengagement of the work piece by the work clamping members together with the rotary movement of the work clamping members to reposition the work before the succeeding operation of the tool.

20. In a machine for glazing leather, a glazing tool, a work support movable to back a work piece against the thrust of the tool, means for moving the tool back and forth in a plane above the work support, a feeler device movable with the tool and arranged to drop off an edge portion of the work piece before the tool reaches such edge portion, means controlled by the feeler member to reverse the direction of movement of the tool as soon as the latter drops off the edge of the work piece, and means to retract the work support during the return movement of the tool so that such return movement is an idle stroke of the tool preparatory to a succeeding operative stroke thereof.

21. In a machine for operating upon hides and skins, a work support, a tool movable over the surface of a work piece on the work support, power means for reciprocating said tool back and forth in a plane above the surface of the work support, means for moving the work support toward and from the tool, and a feeler device contacting the work piece in advance of the tool in the direction of its operative stroke to control said work support moving means in accordance with the thickness of the work piece in the path of the feeler member and tool.

22. In a machine for operating upon hides and skins, a work support, a tool movable over the surface of a work piece on the work support, power means for reciprocating said tool back and forth in a plane above the surface of the work support, hydraulic means comprising a valve mechanism for moving the work support toward and from said tool, and a feeler device movable in advance of the tool during its operative stroke and operative to respond to variations in the thickness of the work piece in the path of the feeler and tool, said feeler member having connections to control said valve mechanism whereby the work support is adjusted to the varying thickness of the work piece during the movement of the tool in its operative stroke.

23. In a machine for treating hides and skins, a work support, a tool movable in a plane above the surface of a work support to operate on a work piece on the support, power means for moving the work support toward and from said plane, power means for moving the tool back and

forth in its operative and idle strokes, a feeler device contacting the work piece and movable in advance of the tool in its operative stroke, and connections between the feeler device and both of 5 said power means whereby the feeler member controls not only the length of the operative stroke of the tool but also the position of the work support in accordance with variations in the thickness of the work piece in the path of 10 the tool over the latter.

24. In a machine for operating upon hides and skins, a work support, a tool for treating a work piece while the latter is backed by the support, hydraulic means comprising a piston device having operative connections with said tool, cylinders for slidably receiving the opposite ends of 15 said piston device, a valve mechanism to control the passage of pressure medium alternately to said cylinders, whereby the piston device and the tool are reciprocated, a feeler device contacting the work piece and movable in advance of the tool in the direction of its operative stroke, connections between the feeler device and said valve mechanism to control the latter whereby 20 the piston device and hence the tool are reversed in their direction of movement when the feeler drops off an edge of the work piece, hydraulic mechanism to move the work support toward and from the tool, and connections between said feeler member and the hydraulic mechanism to control the movement of the work support in accordance with the thickness of the work piece in the path of the feeler member.

25. In a machine for operating upon hides and 35 skins, a work support, a tool movable from a middle portion of a work piece to a margin thereof, hydraulic means for reciprocating the tool in its operative and idle strokes, a pair of work clamping members on each side of the work support, one of each pair being above and the other below the work supporting surface thereof, thus providing an upper and a lower set of clamping members, power means for moving one set of work clamping members toward 40 the other whereby the work piece is clamped by said clamping member, and hydraulic mechanism operating in timed relation to the hydraulic means to move the clamping members to shift the work piece in one direction over the surface of the work support prior to the operation of the tool.

26. In a machine for operating upon hides and skins, a work support, a tool movable from a middle portion of a work piece to a margin thereof, 55 hydraulic means for reciprocating the tool in its operative and idle strokes, a pair of work clamping members on each side of the work support, one of each pair being above and the other below the work supporting surface thereof, thus providing an upper and a lower set of clamping members, power means for moving one set of work clamping members toward the other whereby the work piece is clamped by said clamping members, means to move the clamping members 60 to shift the work piece in one direction over the surface of the work support prior to the operation of the tool, and hydraulically operated mechanism operating in timed relation to said hydraulic means to move the clamping members 65 to shift the work piece in one direction over the surface of the work support prior to the operation of the tool, and hydraulically operated mechanism operating in timed relation to said hydraulic means to move the clamping members 70 on each side of the work support away from each other sufficiently to place the work piece under tension prior to the operation of said tool.

27. In a machine for operating upon hides and skins, a work support, a tool movable from a middle portion of a work piece to a margin there-

of, hydraulic means for reciprocating the tool in its operative and idle strokes, a pair of work clamping members on each side of the work support, one of each pair being above and the other below the work supporting surface thereof, thus providing an upper and a lower set of clamping members, power means for moving one set of work clamping members toward the other whereby the work piece is clamped by said clamping members, means to move the clamping members to shift the work piece in one direction over the surface of the work support prior to the operation of the tool, hydraulic mechanism operating in timed relation to said hydraulic means for causing relative approaching and separating movements between the work support and tool in a direction to press the work piece against the tool, and means for causing a separating movement of the clamping members on each side of the table to place the work piece under tension just prior to the pressing of the work piece against the tool, the means for operating the tool being operative while the work piece is held by the work clamping members.

28. In a machine for operating upon hides and skins, a work support, a tool movable from a middle portion of a work piece to a margin thereon, hydraulic means for reciprocating the tool in its operative and idle strokes, a pair of work clamping members on each side of the work support, one of each pair being above and the other below the work supporting surface thereof, thus providing an upper and a lower set of clamping members, hydraulic means for moving one set of work clamping members toward the other whereby the work piece is clamped by said clamping members, means for moving the clamping members to shift the work piece in one direction over the surface of the work support prior to the operation of the tool, the work support being movable in a direction to press the work piece against the tool, hydraulic means operating in

timed relation to the two hydraulic means above mentioned for causing a separating movement of the clamping members on each side of the table to place the work piece under tension just prior to the operation of the tool, said means for operating the tool being operative to treat the work piece while it is held under tension by the work clamping members, and means for lowering the work support and at the same time returning the work clamping members to their initial positions, whereby the work piece is released by both the work support and the work clamping members, the subsequent upward movement of the work support and of the lower set of the work clamping members being accompanied by reengagement of the work piece by the work clamping members together with a rotary movement of the work clamping members to reposition the work before the succeeding operation of the tool.

29. In a machine for operating upon sheet material, the combination with a work support and a tool, of power operated means for imparting to said tool repeated back-and-forth movements in operating upon a work piece on said support, and work-controlled means for reversing that movement of the tool which ends with the latter dropping off the edge of the work piece, said work-controlled means becoming operative to reverse the tool as soon as the latter drops off the work piece.

30. In a machine for operating on sheet material, a tool, a work support for a work piece during treatment thereof, means for moving the tool back and forth in a plane above the work support, a feeler device movable with the tool and arranged to drop off an edge portion of the work piece before the tool reaches such edge portion, and means controlled by the feeler device to reverse the direction of movement of the tool as soon as the tool drops off the edge of the work piece.
